US00D801288S

(12) **United States Design Patent** (10) Patent No.: **US D801,288 S**
Kim et al. (45) Date of Patent: **** Oct. 31, 2017**

(54) **REMOTE CONTROL FOR AIR CONDITIONER**

(71) Applicant: **Samsung Electronics Co., Ltd.**, Suwon-si (KR)

(72) Inventors: **Daejoung Kim**, Seoul (KR); **Youngsun Shin**, Seoul (KR)

(73) Assignee: **Samsung Electronics Co., Ltd.**, Suwon-si (KR)

(**) Term: **15 Years**

(21) Appl. No.: **29/533,757**

(22) Filed: **Jul. 22, 2015**

(30) **Foreign Application Priority Data**

(57) **CLAIM**

We claim the ornamental design for a remote control for air conditioner, as shown and described.

DESCRIPTION

FIG. 1 is a front perspective view of a remote control for air conditioner showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures show portions of the remote control for air conditioner which form no part of the claimed design.
